CLAIM

The ornamental design for a detergent tablet, as shown and described.

DESCRIPTION

The present invention is related to co-pending design application Ser. Nos. 29/097,257, 29/097,249, 29/097,254, 29/097,250, 29/097,258, 29/097,259, 29/121,224, 29/097, 245, 29/099,272, 29/121,871, 29/097,251, and 29/097,255 respectively which were filed herewith.

FIG. 1 is a perspective view of the detergent tablet showing my new design;

FIG. 2 is a front elevational view thereof, the back, right side, and left side elevational views, respectively, being identical thereto; and,

FIG. 3 is a bottom plan view thereof.
